HEDDLE FRAME FOR A WEAVING LOOM

Martin Graf, Horgenberg, Zurich, Switzerland, assignor to Grob & Co., Aktiengesellschaft, Zurich, Switzerland

Application July 1, 1957, Serial No. 669,138

Claims priority, application Switzerland July 2, 1956

6 Claims. (Cl. 139—92)

The present invention relates to a heddle frame for weaving loom having at least one exchangeable intermediate stay rod. In such heddle frames the upper and the lower frame bars of the heddle frame are connected to one another in a manner known in itself at their ends by end rods and by one or more intermediate stay rods which are insertable. Moreover the carrier rails for the heddle are attached at certain intervals on a lateral projection of the frame bars.

The heddle frame for a weaving loom according to the invention is characterised in that said stay rod consists in a single part and has at both ends at least one projection which projections co-operate directly with corresponding recesses of the said heddle frame for the purpose of arresting the said stay rod.

In the accompanying drawing embodiments of the invention are diagrammatically illustrated by way of example, in which:

Fig. 1 is an elevation of a heddle frame for a weaving loom,

Fig. 2 is a section on the line II—II of Fig. 1 through the upper frame bar of the heddle frame on a larger scale,

Fig. 3 is a section on the line III—III of Fig. 1 through the lower frame bar of the heddle frame, on a larger scale, viz., (a) with the stay rod turned 90° while being inserted, (b) with the stay rod inserted,

Fig. 4 is a perspective view of the end of a stay rod,

Fig. 5 is a section through an upper frame bar of the heddle frame in the range of an inserted stay rod of a modification,

Fig. 6 is a section of an upper frame bar of a double-row heddle frame for a weaving loom with a stay rod inserted, and

Fig. 7 is a cross-section taken on line VII—VII in Fig. 6.

The weaving loom heddle frame 1 in Fig. 1 has an upper frame bar 2 and a lower frame bar 3, which are connected with one another by fixed or detachable lateral supports, or end rods, 4. The upper and the lower frame bars each have a part 5 directed towards the center of the frame on which part the heddle carrier rail 6 is fixed in a known manner by rivets 7 or similar means. In other embodiments on the other hand the heddle carrier rails are mounted removably, the lateral parts 5 of the frame bars then being replaced by closure pieces.

In the heddle carrier rails 6 one or more recesses 8 corresponding to the number of stay rods are provided for taking-in the projection at the end of the stay rod 9.

The end of the stay rod 9 is inserted into the interstice bounded by the projection 5 of the frame bar 2 and by the heddle-carrier rail 6, as illustrated in Fig. 2. The end of the stay rod is unilaterally recessed at 10a and at 10b, whereby a projection 11 lying there between is formed which engages in turn into the recess 8 of the heddle-carrier rail 6 (Fig. 4). The elongated faces 11 of the projection 11 converge towards the outer edges in

2

order to facilitate the insertion into the recess 8 of the heddle-carrier rail. The upper and lower supporting faces 12a and 12b of the projection 11 are preferably slightly inclined towards one another in order that the stay rod 9 may be fitted free from rattling into the recess 8 of the heddle carrier rail. The tapered head 13 of the stay rod facilitates the insertion into the interstice between the projection 5 of the frame bar and the heddle carrier rail 6.

At the recessed points 10a and 10b the end of the stay rod is preferably wider than the recess bounded by the part 5 of the frame bar and the heddle-carrier rail 6. The heddle-carrier rails are preferably made of strip steel and allow themselves to be deflected between the individual attachment points 7 provided with suitable spacing to a limited extent away from the projections of the frame bar. The heddle-carrier rail 6 resting on the recessed faces 10a and 10b forces the stay rod 9 against the projection 5 of the frame bar, which results in a good fit free from rattling of the stay rod, as illustrated also in Fig. 3b.

In order to insert the stay rod 9 the same is turned 90° on its vertical axis, and as indicated in Fig. 1 at 9a, is positioned so far at an angle that the tapered heads 13 on the upper and lower end, respectively, can be inserted between the projection of the upper frame bar 2 and the heddle-carrier rail 6 and between the projection 5 of the lower frame bar 3 and the heddle-carrier rail, respectively. Then the stay rod is brought into the vertical position in such a manner that the upper and lower projection 11, respectively, comes to lie by the side of the recess 8 in the upper and lower heddle-carrier rail, respectively. In Fig. 3a the stay rod 9 is shown in this position. Then the stay rod is again turned 90° in order that its projection 11 may engage into the recesses 8 of the heddle-carrier rails.

In this position the heddle-carrier rail 6 comes to rest on the faces 10a and 10b of the stay rods, the interstice between the portion 5 of the frame bar and the heddle-carrier rail 6 is forcibly enlarged and the stay rod is pressed firmly on the projection of the frame bar by the heddle carrier rail which is under stress, and is at the same time also secured against being unintentionally turned.

In Fig. 5 a modification is illustrated in section. On a member bar 14 conveniently formed plates, locking pieces or the like 15 are mounted to form a frame bar 14, 15 for the attachment of the heddle-carrier rail 19. The stay rod 16 has two oppositely positioned projections 17 and 18 which may be arranged at the same level or offset with respect to one another. The projection 17 engages into a recess in the plate 15, and the opposite projection 18 engages into a recess of the heddle-carrier rail 19.

Likewise the stay rod 16 may engage with a projection 17 only into a recess of the plate 15 (Fig. 5) or of the portion 5 of the frame bar (Fig. 2) and be supported on the heddle-carrier bar 19 (Fig. 5) or 6 (Fig. 2). Instead of engaging into a recess of the rail of the frame bar, the stay rod or the projections thereof may engage into notches thereof.

Moreover instead of the portion 5 of the frame bar (Fig. 2) or of the plate 15 (Fig. 5) a second heddle-carrier rail 20 may be used in double-row weaving loom heddle frames which may be arranged at the same level or may be offset. Such an arrangement is illustrated in Figs. 6 and 7.

While I have herein described and illustrated in the accompanying drawings what may be considered typical and particularly useful embodiments of my said invention I wish it to be understood that I do not limit myself to the particular details and dimensions described and

illustrated, for obvious modifications will occur to a person skilled in the art.

What I claim as my invention and desire to secure by Letters Patent is:

1. In a heddle frame, an upper substantially horizontal frame bar, a lower substantially horizontal frame bar, upright end rods interconnecting said upper and lower frame bars at both ends thereof, an upper laterally flexible heddle carrier rail substantially parallel with said upper frame bar in a laterally offset and vertically overlapping relation thereto, a lower laterally flexible heddle carrier rail substantially parallel with said lower frame bar in a laterally offset and vertically overlapping relation thereto, fastening means securing said upper flexible heddle carrier rail to said upper frame bar at spaced intervals, fastening means securing said lower flexible heddle carrier rail to said lower frame bar at spaced intervals, an upright stay rod disposed intermediate said end rods and overlapping said upper and lower frame bars, and lateral locking means on the overlapping portions of said stay rod, whereby said stay rod is releasably clamped between the overlapping portions of the respective frame bar and carrier rail through lateral yielding pressure from said flexible carrier rails. 20

2. The heddle frame as set forth in claim 1, in which said locking means comprises a lateral projection on the overlapping portion of said stay rod adapted for engagement with a corresponding recess in the adjacent flexible carrier rail. 25

3. The heddle frame as set forth in claim 1, in which said locking means comprises a first lateral projection on

the overlapping portion of said stay rod adapted to engagement with a corresponding recess in the overlapping portion of the adjacent carrier rail, and a second lateral projection on the overlapping portion of said stay rod adapted for engagement with a corresponding recess in the overlapping portion of the adjacent frame bar. 10

4. The heddle frame as set forth in claim 3, in which said overlapping portion of the adjacent frame bar comprises a second flexible heddle carrier rail offset an equal distance from the vertical center line of the frame bar as the first mentioned carrier rail but in the opposite direction. 15

5. The heddle frame as set forth in claim 1, in which said stay rod is substantially rectangular in cross-section along the portion of its length in engagement with said carrier rail, whereby it may be inserted with said projection extending substantially parallel with said carrier rail and locked in position by turning said stay rod through an angle of 90° about its longitudinal axis. 20

6. The heddle frame as set forth in claim 1, in which the lateral dimension of said intermediate stay rod is greater than the distance between the members engaging it on opposite sides when in locked position. 25
